Patented Nov. 11, 1975

237,598

TRUCK BOX SIDE PANEL

Jerry Edward Jacobs, Northwood, Iowa, assignor to
Winnebago Industries, Inc., Forest City, Iowa

Filed May 3, 1974, Ser. No. 466,697

Term of patent 14 years

Int. Cl. D12—16

U.S. Cl. D12—98

FIG. 1

FIG. 2

FIG. 3

FIG. 4

FIG. 5

FIG. 6

FIG. 7

FIG. 8

FIG. 9

FIG. 10

FIG. 1 is a top plan view of a truck box side panel showing my new design;

FIG. 2 is an outside elevational view thereof;

FIG. 3 is an inside elevational view thereof;

FIG. 4 is a bottom plan view thereof;

FIG. 5 is a right end elevational view, the left end being a mirror image thereof;

FIG. 6 is a top plan view of a truck box side panel showing a second embodiment of my new design;

FIG. 7 is an outside elevational view of FIG. 6;

FIG. 8 is an inside elevational view of FIG. 6;

FIG. 9 is a right end elevational view of FIG. 6, the left end being a mirror image thereof; and

FIG. 10 is a bottom plan view of FIG. 6.

I claim:

The ornamental design for a truck box side panel, substantially as shown.
